UNITED STATES PATENT OFFICE.

PETER H. SMITH, OF ST. PAUL, MINNESOTA.

LIMOUSINE BODY FOR BABY CARRIAGES.

1,403,451.

Specification of Letters Patent. Patented Jan. 10, 1922.

Application filed March 24, 1921. Serial No. 454,988.

To all whom it may concern:

Be it known that I, PETER H. SMITH, a citizen of the United States, residing at St. Paul, in the county of Ramsey and State of Minnesota, have invented certain new and useful Improvements in Limousine Bodies for Baby Carriages, of which the following is a specification.

My invention relates to limousine bodies for baby carriages. An object is to provide a device of this character which may be entirely closed to protect the child from the weather and which may be opened up to any desired extent to admit air. Another object is to provide a device of this character in which the top portion may either be entirely removed during warm weather or in which frames containing glass may be replaced by frames containing screen material.

The full objects and advantages of my invention will appear in connection with the detailed description, and the novel features embodied in my inventive idea will be particularly pointed out in the claims.

In the accompanying drawings which illustrate the application of my invention in one form, —Fig. 1 is a side elevational view of my device showing it in closed position in full lines and in opened position in dotted lines. Fig. 2 is a longitudinal sectional view of the device detached from the supporting construction. Fig. 3 is a rear elevational view of the body. Fig. 4 is a fragmentary view showing the manner of attaching a hinge. Fig. 5 is a view in section on the line 5—5 of Fig. 4. Fig. 6 is a side elevational view in which the entire superstructure has been removed. Fig. 7 is a plan view of a hinge in which one hinge member overlies another hinge member. Fig. 8 is a plan view of the lower hinge member; Fig. 9 is a plan view of the upper hinge member; Fig. 10 is a view in section on the line 10—10 of Fig. 7; Fig. 11 is a view in section on the line 11—11 of Fig. 7; Fig. 12 is a view in section on the line 12—12 of Fig. 7; Fig. 13 is a view similar to Fig. 12 but showing the hinge partly opened; Fig. 14 is a view similar to the two preceding

views but showing the hinge opened into its position for separating the two members. Fig. 15 is a view in section on the line 15—15 of Fig. 2. Fig. 16 is a view in section on the line 16—16 of Fig. 2. Fig. 17 is a view in section on the line 17—17 of

Fig. 1. Fig. 18 is a side elevational view of a detachable screen member.

As shown in the drawings, the limousine body comprises a box portion 20 and a cab portion 22, the latter being hinged to the box portion as indicated generally at 24. The box portion 20 may be mounted for use in suitable manner as by securing it to springs 26 associated with a frame mounted on wheels 28 so that the carriage may be pushed by handles 30. The box portion 20 in front of the cab portion 22 is provided with a cover 32 which is hinged to one of the side members of the box by separable hinges such as shown in Figs. 7 to 14. Each of the hinges consists of a lower member 34 and an upper member 36. The lower member 34 as best shown in Fig. 8 has two cutout portions 38 which are bridged by a pintle member 40 fixedly mounted in upstanding hollow cylindrical members 42, and the pintle member where it bridges the two openings 38 has cut-away flat portions 44. The upper member 36 is shown in Fig. 9 removed from the lower member but occupying the same relative position which it occupies in Fig. 7. The upper member has three cutout portions 46 which receive the cylindrical members 42 when the two hinged members are attached together. The upper member between the middle cutout portion and the cutout end portions is provided with hooks 48 adapted to turn upon the two exposed portions of the pintle 40. The operation of the hinge will be apparent from Figs. 13 and 14 from which it will be seen that when the upper member 36 is turned through a little more than 180° it may be readily separated from the lower hinged member. By comparison with Fig. 17, it will be understood that the cover 32 may be removed from the box portion 20 upon rotating the cover through a little more than 180°. The cab portion 22 is hinged to the rear end of the box member by hinges which are similar to those already described but which are narrower as shown in Figs. 4 and 5, the lower member 50 having only one cutout portion bridged by a pintle 52 and the upper member 54 having a single hook 56 to engage the pintle. These two sets of separable hinges permit the cab portion 22 and the cover 32 to be readily removed so that the box portion 20 may be placed in open condition as shown in Fig. 6. The

cab portion when in place is held by a suitable catch such as the catch 58 shown in Fig. 1. The cab portion is provided with a top or cover 60, the rear edge of which is hinged at 62. Hinged to the front of the cover 60 is a shield member 64 which may occupy a vertical position so that its lower edge fits closely above an upstanding flange 66 on the cover 32. Pivots attached to 10 the shield member is a bar 68 which passes through a staple 70 secured to the side of the cab portion so that ratchet teeth 72 on the lower edge of the bar may engage the staple and hold the shield member in raised 15 forward position as shown in Fig. 1 to admit air. The side of the cab portion near its top is provided with a second staple 74 so that when the cover 60 is swung on its hinges 62 one of the notches in the bar 68 20 may be engaged with this staple to hold the cover 60 and the shield 64 in the position shown in dotted lines in Fig. 2 so that more air may be admitted. The bar 68 is provided with a notch 76 on its upper edge so that 25 when the catch 58 is released and the cover 60 is pulled upwardly, this notch will engage the staple 70 and the whole cab portion, including the cover 60 and the shield 64, will swing backwardly as shown in dotted lines in Fig. 1. A detachable chain 78 shown in Fig. 2 may be secured at its ends to the box portion and the cab portion respectively so as to limit the amount of this rearward movement. The back of the cab 35 may be provided with an opening filled with glass to constitute a window 80 as shown in Fig. 3. The shield 64 is provided with a slideway to receive a frame 82 containing glass 84 for use in cool weather. During 40 warm weather, the frame 82 may be removed and replaced by a frame 86 containing screen material 88. In order to hold these frames in place, they are preferably provided with a pin 90 adapted to engage a flat spring 92 45 in the slideway. As shown in Fig. 15, the sides of the cab may also be provided with slideways for receiving removable frames 94 which may contain glass or screen material according to the particular season of the 50 year.

The operation and advantages of my invention have to a large extent been set forth in connection with the foregoing description. The device is so constructed that it 55 may be readily changed from a closed condition to a condition which is open to any desired extent for admitting air. For use in warm weather, the superstructure may be

removed entirely or if desired, the glass frames may be replaced by screens for keeping out insects. It will be obvious from Fig. 2 that the body may be mounted upon any suitable supporting structure.

I claim:

1. A limousine body for baby carriages comprising a box member, a cover for the forward portion of said box member, separable hinges for attaching said cover to said box member, a cab member extending above the rear portion of said box member and separable hinges for attaching the rear wall of said cab member to said box member.

2. A limousine body for baby carriages comprising a box member, a cover for the forward portion of said box member, a cab member attached to the rear portion of said box member, a cover hinged to the upper end of the rear wall of said cab member, a shield member hinged to the front of said cover, and means for adjustably holding said shield member in a more or less opened position.

3. A limousine body for baby carriages comprising a box member, a cover for the forward portion of said box member, a cab member attached to the rear portion of said box member, a cover hinged to the upper end of the rear wall of said cab member, a shield member hinged to the front of said cover, a ratchet bar hinged to the lower portion of said shield member, and an engageable member on said cam member for engagement by said ratchet bar.

4. A limousine body for baby carriages comprising a box member, a cover for the forward portion of said box member, a cab member hinged to the rear wall of said box member, a cover hinged to the upper end of the rear wall of said cab member, a shield member hinged to the front of said cover, a bar hinged to the lower portion of said shield member and having ratchet teeth on its lower edge and a notch in its upper edge, a staple on said cab member through which said bar is adapted to extend, said staple being adapted for engagement by said ratchet teeth for holding said shield member in opened position, and also being adapted for engagement in said notch when said cab cover is lifted, and a second staple on said cab member adapted for engagement with said ratchet teeth for holding said cab cover in raised position.

In testimony whereof I hereunto affix my signature.

PETER H. SMITH.
